UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR A HANGER FOR LIGHT-REFLECTING BOWLS.

47,923.

Specification for Design.

Patented Oct. 5, 1915.

Application filed April 21, 1915. Serial No. 22,965. Term of patent 7 years.

To all whom it may concern:

Be it known that I, CHARLES E. JONES, a citizen of the United States, residing at Chicago, in the county of Cook and State of Illinois, have invented a new, original, and ornamental Design for a Hanger for Light-Reflecting Bowls, of which the following is a specification, reference being had to the accompanying drawing, forming part thereof.

The figure is a perspective view of a

hanger for light reflecting bowls, showing my new design.

I claim:

The ornamental design for a hanger for light reflecting bowls, as shown.

CHARLES E. JONES.
